UNITED STATES PATENT OFFICE.

HENRY LAWRENCE BREINIG AND CHARLES OTTO BREINIG, OF TERRE HAUTE, INDIANA.

AMUSEMENT DEVICE.

1,334,592.

Specification of Letters Patent. Patented Mar. 23, 1920.

Application filed March 24, 1919. Serial No. 284,855.

To all whom it may concern:

Be it known that we, HENRY LAWRENCE BREINIG and CHARLES OTTO BREINIG, both citizens of the United States, residing at Terre Haute, in the county of Vigo and State of Indiana, have invented new and useful Improvements in Amusement Devices, of which the following is a specification.

This invention relates to amusement devices, and has for its primary object to provide a novel structure for use in pleasure parks and other amusement resorts, and whereby the occupants of the cars carried by the device and involving a part thereof are caused to be confused and thus entertained and pleased by being passed through a diversity of courses or movements.

A further object of the invention is to provide a pleasure apparatus which, while being capable of highly entertaining the occupants of its cars, is of simple construction, which may be erected easily and quickly, which may be operated with facility and at low expense, and which will prove thoroughly durable in practice.

With these objects in view, together with others which will appear as the description proceeds, the invention resides in the novel construction, combination and arrangement of parts, all as will be described more fully hereinafter, illustrated in the drawing, and particularly pointed out in the claims.

In the drawings—

Figure 1 is a top plan view of an amusement device constructed in accordance with the invention,

Fig. 2 is an end view of the amusement device,

Fig. 3 is a side view, with parts broken away, and

Fig. 4 is a detail fragmentary section showing the manner in which the supporting shafts for the wheels are connected with the driving mechanism.

Referring now more particularly to the drawings, 5 indicates a circular track supported by beams or posts 6 a considerable distance above the ground in such a manner that the trackway is disposed horizontally. The framework supporting this track also includes a number of reinforcing or bracing beams or studs 7, so that the structure will possess sufficient rigidity and strength to withstand the strains and stresses which

it must of necessity bear. The track 5 in the present instance is shown as being constructed of angle iron, although it may be built otherwise if desired. The supporting framework may be of channel or angle irons or of wood beams. The circle defined by the track 5 has arranged concentrically therewith a bevel gear trackway 8, the latter being supported by the annular member 9. As shown, this bevel gear trackway is of greatly less diameter than the track 5.

The amusement device includes a pair of axles 10 and 11, each of which has secured thereto a wheel 12 to travel upon the trackway 5, and the inner ends of these axles are disposed close together at the center of the circle defined by the track. These inner ends of the alined axles are connected together by means of the coupling member indicated at 13, and set screws 14 passing through the union or coupling member 13 engage at their inner ends in grooves 15 near the inner extremities of the axles to prevent the latter moving longitudinally. It will be seen that this particular construction enables the axles to rotate independently of each other and yet they are connected together at their inner ends.

The union or coupling member receives the upper end of a drive shaft 16, the latter being provided near its lower end with a bevel gear 17 in mesh with a pinion 18 carried by the shaft of a motor or other source of power indicated at 19. With reference to Fig. 4 of the drawing, it will be seen that the shaft 16 is squared at its upper end and is engaged in a similarly shaped recess in the coupling member, whereby rotary movement applied to the driving mechanism will cause the union to turn independently.

Each of the axles 10—11 is provided with a bevel gear 20 engaged with the gear trackway 8, so that rotary movement applied to drive shaft 16 will cause the axles to rotate and prevent slippage. This particular bevel gear and trackway construction also assists in maintaining uniform and steady movement of the axles.

The outer end of each axle has secured thereto a vertically disposed wheel indicated at 21. These wheels are relatively large and are of sufficient width to contain therein tracks indicated at 22. These tracks extend entirely around the wheel periphery, and are engaged by the wheels 23 of cars 24, 110

The cars are provided with seats 25 of any size or number to accommodate the passengers. Each wheel 21 is provided with spaced guard rails 26, to prevent the cars 5 moving laterally of their supporting trackways. It will be observed, particularly with reference to Fig. 2, that the wheels 21 are provided in their outer peripheries with inwardly curved portions indicated at 27, 10 whereby "rises" in the tracks 22 are formed. These "rises" may be provided at any place in the circumference of the wheel and in any number, and it is obvious that as the wheels 21 rotate and the "rises" pass beneath the 15 cars 24, the latter will be caused to move up and down, thereby adding to the amusement of the occupant.

After the cars are occupied, the motor 19 is started. This causes shaft 16 to rotate 20 and to impart whirling and rotary movement to the axles 10—11. The wheels 21 are thus caused to rotate and at the same time to move bodily in a circle. The weight of the cars and their occupants maintains the 25 cars always at the lower side of the wheel, whereby the trackway passes beneath the cars. The movement of the supporting wheel relative to the cars, the bodily movement of the wheel in a circle, and the undulations in the track cause confusion to the car occupants, whereby the attractiveness of the device is enhanced.

Cars in any number may be arranged within each wheel, and the cars are preferably 30 connected together to prevent accident.

An amusement device of this character combines the attractive features of the 35 carousel, roller coaster and Ferris wheel and

eliminates the shock producing and nerve racking features of such devices.

While the above is a description of the preferred embodiment of the invention it is obvious that changes in the arrangement and details may be resorted to without departing from the spirit of the invention as defined 45 by the claims.

We claim:—

1. In an amusement device, a pair of alined axles, a shaft disposed between the adjacent ends of the said axles and at right 50 angles to the latter, a squared portion on the shaft end, a sleeve having a squared bore resting upon said shaft end, hollow tubular portions projecting from the sides of said sleeve, the axle ends being rotatably mounted in said tubular portions, and means for holding said axles against longitudinal movement in said tubular portions.

2. In an amusement device, a pair of alined axles arranged in spaced relation, a 60 shaft disposed between the adjacent ends of said axles and at right angles to the latter, a squared portion on the said shaft adjacent to the axle ends, a sleeve having a squared bore fitting upon said shaft end, hollow 65 tubular portions projecting from the sides of said sleeve and inclosing the shaft ends, each of said shaft ends inclosed by said sleeves having an annular groove, and set screws threaded in said sleeves and extending into 70 said grooves.

In testimony whereof we affix our signatures.

HENRY LAWRENCE BREINIG.
CHARLES OTTO BREINIG.
